UNITED STATES PATENT OFFICE.

GEORGE L. REICHHHELM, OF NEW HAVEN, CONNECTICUT.

APPARATUS FOR AND PROCESS OF BURNING GAS.

1,227,829.

Specification of Letters Patent. Patented May 29, 1917.

Application filed September 4, 1915, Serial No. 48,962. Renewed April 16, 1917. Serial No. 162,521.

To all whom it may concern:

Be it known that I, GEORGE L. REICHHHELM, a citizen of the United States, residing at New Haven, in the county of New Haven and State of Connecticut, have invented certain new and useful Improvements in Apparatus for and Processes of Burning Gas, of which the following is a specification.

This invention relates to improvements in the process and apparatus for burning gas or gaseous mixtures, and has for its main object to provide apparatus and process of this nature which will permit direct burning and combustion of gaseous fuel supplied under high pressure to the burner proper.

Ordinarily in the combustion of gas mixed with air it is necessary to supply the mixture at a comparatively slow rate to the burner to permit proper flame propagation; otherwise the flame will be blown out from the burner. In utilizing my process and apparatus, I am enabled to supply the combustible mixture under high pressure without affecting the combustion thereof, or interfering with the propagation of the flame.

Another object of the invention is to provide apparatus of the class described which will intimately and thoroughly mix the fuel with the air, so as to secure the most efficient combustion possible.

Still another object is to provide a burner of a tubular nature in which the combustion of the combustible mixture will take place, such combustion being arranged to take place in a focus or approximately centrally located portion of the interior of a burner, which enables me to secure a burner core of high temperature without melting or unduly heating the burner tube.

These and other objects will be more fully set forth and described in the following specification, taken in connection with the accompanying drawings, in which—

Figure 1 is a side elevation of my apparatus;

Fig. 2 is a vertical section through a portion of the same.

Fig. 3 is a similar section through another portion of the same.

Fig. 4 is a front elevation of the forward perforated burner plate.

Fig. 5 is a side elevation of the same.

Fig. 6 is a side elevation of the rear burner plate.

65

Fig. 7 is a front elevation of the same.

Fig. 8 is a side elevation of the burner tube; and

Fig. 9 is a front elevation of the same.

Like numerals refer to like elements 60 throughout the drawings, in which—

9 indicates generally an air supply pipe having a valve 9^a to control flow of air therethrough, and terminating at and connected to a T 9^b. 10 is a gas supply duct or pipe having the controlling valve 10^a terminating in and attached to the T 10^b. Attached to these T's 9^b and 10^b is the main duct 11, of which they form a portion, as shown in Fig. 3, for example. This duct is 70 provided with a tapered nozzle portion 11^a projecting forwardly of the gas duct 10, see Fig. 3—and projecting into a continuation of the duct 11 formed by the pipe 11^b, which pipe in turn is threaded into a coupling 12, the other end of which is enlarged, as indicated by numeral 12^a. In this enlarged end is threaded the pipe or tube section 13, at one end of which is mounted 75 a burner disk or plate 14, having the centrally located aperture 14^a therethrough and the outwardly projecting flange or boss 14^b provided with the apertures or notches 14^c—see Figs. 4 and 5, for example. Alter-

native of these notches 14^c are larger in size, 80 as shown in Fig. 4. A peripheral groove 14^d is provided between the apertured flange 14^b and main head of the disk or plate 14, against the rear face of which abuts one end 85 of the burner tube 15. In this burner tube 90 is closely fitted the flange or collar 14^b, as shown in Fig. 2. Apertures 15^a are provided at one end of the tube 15 to communicate with the peripheral groove 14^d of the burner plate 14. This latter is held against 95 a shoulder 16^a of the combustion tube 16, in one end of which it is held by the tube 13—see Fig. 2. The apertured internally threaded boss 16^b projects outwardly from the tube 16, and in this boss is threaded a spark 100 plug, generally indicated by numeral 17.

Mounted in the burner tube 15, adjacent one end thereof, is the burner plate or disk 18, having notches 18^a therethrough, as shown in Figs. 2 and 7, alternate of these 105 notches being larger in size than their

neighbor, as in the case of burner plate 14. For adjustment purposes this disk 18 is attached to the rod 19 projecting rearwardly through the coupling 12, tube 11^b, duct 11, and out through the T 9^b, in the end of which is threaded a gland or stuffing box member 20. The rod 19 is threaded to engage internal threads in the apertured gland member 20, and may be provided with an operating handle 19^a, whereby the rod 19 may be rotated and advanced into or drawn out of the tubes in order to move the burner plate 18 toward or from burner plate 14.

In the use of my apparatus the valves 9^a and 10^a may be opened, and the air flowing through tube 11 and nozzle portion 11^a will set up an injector action where pressure of the pure gas flowing through inlet pipe 10 is low, and in any event will serve to mix and commingle thoroughly the gas and air in the mixing tube 11^b. From this tube the fuel mixture may flow at high pressure into the coupling 12 and tube 13. Part of the mixture will flow through the apertures 18^a in disk 18 into the tube 15, while the remainder will flow around tube 15, through the apertures 15^a therein, and into the tube 15 through apertures 14^a in burner plate 14.

The small streams or currents of the combustible mixture flowing through the notches or apertures 14^a and 18^a are directed along the inner wall of the burner tube 15, owing to the inclined arrangement of said notches. In the embodiment shown, a spiral or rotatory movement will be imparted thereto. The currents from the respective disks and plates 14 and 18 meet and oppose each other, so that the velocity of the inflowing mixture of currents is temporarily baffled or retarded, owing to such mutual opposition. During the normal operation of the burner, ignition takes place in the tube 15, as will be more fully explained, and even when operating under comparatively great pressure temporary baffling or retardation of the mixture permits such combustion to take place regardless of the pressure. The ignited mixture then flows out through the aperture 14^a, through the end of the tube 15. To provide for initial ignition, as shown, a spark plug 17 is mounted in a flanged, internally-threaded sleeve 16^b extending upwardly from the tube 16. A shut-off cock 16^a is provided in some instances adjacent the end of the tube 16 and outwardly of the point of burning.

When starting the apparatus the mixture may be allowed to flow at a reduced rate and ignited through the medium of spark plug 17, when the ignition will flash back through the burner tube, through the opening 14^a, assuming that the burner cock is open to permit flow of the gas. The pres-

sure of the supply of mixture may then be increased to the point desired, the baffling or retardation in the burner tube 15 permitting continuous combustion, as explained above. By arranging the notches 14^a, 18^a in inclined position, a resulting swirl or rotatory movement is imparted to the gas along the walls of the tube 15, and a maximum of travel of the gas takes place, so that a thorough and efficient combustion and mixture is insured for the size of the burner tube, as will be apparent. At the same time the flame in said tube is directed toward the longitudinal axis thereof, away from the inner walls of the same, so that I can obtain an axial core or focus for the flame, which may be of high temperature—in fact higher than the melting point of the tube 15, the mixture currents flowing along the inner wall thereof serving to prevent overheating of the tube.

Another feature of my invention is being able to control the flow of the flame outwardly of the ignition point by means of the shut-off cock 16^a, as it will be apparent that when the same is closed during combustion, the pressure will immediately rise in the burner and communicating ducts, offsetting the pressure of the supply, so that no flow taking place, no ignition is possible. The apertures or notches 14^a, 18^a are also preferably constructed so small that back firing is impossible from the burner tube 15. Furthermore, during the normal combustion of the mixture the velocity of the current through these notches or apertures is so great as to prevent such back firing.

While I have contemplated a large number of uses to which my invention may be put, I do not feel it advisable or necessary to include the same herein. It will be apparent to those skilled in the art that by the utilization of my process and apparatus, a flame may be secured and delivered at high pressure and great velocity without affecting the combustion and flame propagation, as mentioned above.

It will be obvious that my invention as shown and described above is susceptible of many modifications and improvements; and I do not therefore wish to be restricted to the form shown and described beyond the scope of the appended claims.

What I claim is:

1. A process of combustion consisting in first supplying a combustible gaseous mixture, then dividing the same into a plurality of streams, retarding the velocity of the streams below the rate of flame propagation by directing them toward each other from opposite directions, and then igniting such mixture at the point of retardation.

2. A process of combustion consisting in first supplying gas and air under pressure,

next mixing the same, reducing the velocity of the mixture below the rate of flame propagation by introducing such mixture through opposed openings into a chamber, and then igniting the same.

10 3. A process of combustion consisting in first supplying gas and air under pressure, next mixing the same, reducing the velocity of the mixture below the rate of flame propagation by introducing such mixture through opposed openings into a chamber, then igniting the same, and then discharging the burning mixture from said chamber through an outlet.

15 4. A process of combustion consisting in first supplying gas and air under pressure, next mixing the same, then dividing said mixture into a plurality of streams, then retarding the velocity of the streams below 20 the rate of flame propagation by directing them toward each other from opposite directions, and then igniting the mixture.

25 5. In an apparatus of the class described, a mixing chamber, means to introduce gas and air under pressure to said chamber, a duct leading from said mixing chamber, a second chamber, spaced apertured partition members located in said second chamber through which the mixture from said duct 30 passes in opposed streams into said second chamber, and means to ignite said mixture.

35 6. In an apparatus of the class described, a burner having a combustion chamber, means to supply combustible mixture to said burner, means to divide said mixture into a plurality of streams or currents, means to retard the velocity of said streams below the rate of flame propagation in supplying the same to the combustion chamber of said 40 burner, and means to ignite said mixture.

45 7. In a device of the class described, a tube, a second tube located therein and spaced therefrom, spaced perforated partition members mounted in said second tube, and means to supply combustible mixture under pressure to said first named tube and thence in opposite directions through said 50 perforated members to the space in said second tube between said members.

55 8. In a device of the class described, a tube, a second tube located therein and spaced therefrom, spaced perforated partition members mounted in said second tube, and means to supply combustible mixture under pressure to said first named tube and thence in opposite directions through said 60 perforated members to the space in said second tube between said members, one of said partition members being provided with an outlet aperture therethrough.

65 9. In a device of the class described, a tube, a second tube located therein and spaced therefrom, spaced perforated partition members mounted in said second tube, and means to supply combustible mixture under 70

pressure to said first named tube and thence in opposite directions through said perforated members to the space in said second tube between said members, one of said partition members being provided with an outlet aperture therethrough, and a chamber communicating with said outlet aperture.

75 10. In a device of the class described, a tube, a second tube located therein and spaced therefrom, said second tube being provided with peripheral apertures adjacent one end thereof, an apertured plate projecting within said second tube, the apertures in said plate being in communication with the apertures in said tube, a second 80 partition plate mounted in said second tube adjacent the other end thereof, said second plate being apertured, and means to supply a combustible mixture under pressure to said first named tube, whereby it will flow 85 through said apertured plates into said second tube.

90 11. In a device of the class described, a tube, a second tube located therein and spaced therefrom, said second tube being provided with peripheral apertures adjacent one end thereof, an apertured plate projecting within said second tube, the apertures in said plate being in communication with the apertures in said tube, a second 95 partition plate mounted in said second tube adjacent the other end thereof, said second plate being apertured, and means to supply a combustible mixture under pressure to said first named tube, whereby it will 100 flow through said apertured plates into said second tube, one of said plates being provided with an outlet aperture leading from said second tube.

105 12. In a device of the class described, a combustion tube, means to supply a combustible mixture under pressure and to admit said mixture in opposed mutually baffling streams to said combustion tube, and means to ignite and burn said mixture in 110 said tube.

115 13. In a device of the class described, a combustion tube, means to supply a combustible mixture under pressure and to admit said mixture in opposed mutually baffling streams to said combustion tube, means to ignite and burn said mixture in said tube, an outlet tube communicating with said combustion tube, and a shut-off cock in said outlet tube.

120 14. A gaseous fuel burner of the class described, comprising a combustion chamber, means for supplying opposed mutually baffling streams of a combustible mixture under pressure to said chamber, and a valve controlling the outlet from said chamber.

125 15. A process of combustion consisting in supplying a combustible mixture in opposed mutually baffling currents of greater velocity than the rate of flame propagation,

- and burning said mixture in the zone where the velocity of said opposed currents has been reduced below the rate of flame propagation through the meeting of said currents.
- 5 18. A process of combustion consisting in supplying a combustible mixture in opposed currents of greater velocity than the rate of flame propagation, confining said mixture to an inclosed space at the point where 30
10 the velocity of said opposed currents is reduced below the rate of flame propagation through a mutual baffling action, burning said mixture in said space and regulating the rate of combustion of said mixture by 35
15 adjusting the size of the outlet from said inclosed space.
17. A process of burning a combustible mixture under high pressure which consists in supplying said mixture to an inclosed space in a stream, the velocity of 40
20 which is greater than the rate of flame propagation, baffling said stream in said inclosed space to reduce the velocity thereof below the rate of flame propagation, igniting said mixture at the baffling point of the 45
25 stream thereof, and regulating the rate of combustion of said mixture by the back pressure to which said space is subjected.
18. A process of combustion consisting in supplying opposed currents of a combustible mixture to an inclosed space, imparting to said streams spiral paths of movement adjacent the periphery of said inclosed space, and burning said mixture in the zone where said opposed currents meet. 50
19. In a gaseous fuel burner of the character described, an inclosed chamber, spaced partitions within said chamber, restricted passages being formed adjacent the peripheries of said partitions leading to the space within said chamber between said partitions, said passages extending at an angle to the axis of said chamber, means for supplying a combustible mixture under pressure to the exterior of said partitions, where by the flow of the mixture through said passages imparts a spiral path to the mixture adjacent the inner surface of said chamber, and means for igniting the mixture within said chamber.

In testimony whereof, I have subscribed my name.

GEORGE L. REICHHHELM.
